APPARATUS FOR VACUUMIZING AND GASSING CONTAINERS

Filed June 27, 1936

UNITED STATES PATENT OFFICE

2,064,678

APPARATUS FOR VACUUMIZING AND
GASSING CONTAINERSWilliam H. Morgan, New York, N. Y., assignor to
Continental Can Company, Inc., New York,
N. Y., a corporation of New York

Application June 27, 1936, Serial No. 87,778

2 Claims. (CL. 226—68)

The invention relates to new and useful improvements in an apparatus for vacuumizing and gassing containers preparatory to the sealing of the same so that the product within the container is maintained in a non-oxidizing atmosphere.

An object of the invention is to provide an apparatus wherein the containers are passed in succession through a vacuum chamber and then a gassing chamber with a valve between said chambers for conveying the cans from one chamber to the other, and wherein the entrance and discharge ends, respectively, of said chambers are so disposed relative to each other that a single valve may be utilized for delivering the containers in succession to the vacuum chamber and for receiving and discharging the containers in succession from the gassing chamber.

In the drawing—

20 The figure is a horizontal sectional view through an apparatus embodying the invention.

The apparatus embodying the invention includes a casing having a partition extending longitudinally thereof, which divides the casing into two independent chambers. Means is provided whereby one of the chambers is adapted to be placed under vacuum and means is provided whereby the other chamber is adapted to be continuously supplied with an inert gas, such as carbon dioxide gas. At the discharge end of the vacuum chamber and the receiving end of the gassing chamber, the casing is provided with a valve seat which is curved about a center and which is provided with openings leading, respectively, from the vacuum chamber and to the gassing chamber.

The valve cooperating with said valve seat is provided with a series of pockets. As the valve rotates, a pocket is presented to the opening leading from the vacuum chamber and a container is discharged into the valve. The valve carries the container to the opening leading to the gassing chamber and the container is removed from the valve pocket and discharged into the gassing chamber. Suitable means is provided for conveying the container along the vacuum chamber and for positively placing the container in the pocket of the valve.

Suitable means is also provided for removing the container from the pocket of the valve and for feeding the container along the gassing chamber. At the opposite end of the casing from the valve just described, there is a valve seat having openings leading to the vacuum chamber and from the gassing chamber, respectively. There is also a valve having pockets which cooperates with the valve seat. Means is provided for feeding

containers in succession into the pockets of the valve as it rotates, and means is provided for removing a container from a pocket and placing the same into range of movement of the feeding mechanism operating in the vacuum chamber. Means is also provided for engaging a container at the delivery end of the gassing chamber for placing the same in the pocket of the valve. Means is likewise provided for removing the containers from the valve for discharge from the apparatus.

Referring more in detail to the drawing, the apparatus includes a main casing having the side walls 1 and 2. This casing is mounted on a suitable frame and is closed at its bottom and also at its top. Extending longitudinally of the casing is a hollow partition 3 which separates the casing into two independent chambers 4 and 5.

The casing is provided with an extension 6 forming a chamber 7 which communicates with the vacuum chamber 4. It is also provided with an extension 8 forming a chamber 9 which communicates with the gassing chamber 5. The casing has a central extension 10 which separates the chambers. A valve seat 11 curved about a center 12 is attached to the extension 6, the extension 8 and also to the central extension 10. This valve seat has an opening 13 leading to the chamber 7 and also an opening 14 leading to the chamber 9. There is an extension 15 secured to the valve seat 11 and curved about the center 12. There is also an extension 16 secured to the valve seat 11 and curved about the center 12. These valve seats together with the suitable bottom and top connections constitute the valve housing.

A valve 17 is mounted for rotation about the center 12 in said valve housing, and this valve contacts with the valve seat 11 and the extensions 15 and 16 thereof. The valve is provided with a series of pockets 18, 18. The valves and the pockets therein are of substantially the same construction as the valves shown in the Troyer Patent #1,983,252, granted December 4, 1934, and further detail description thereof is not thought necessary.

The containers are conveyed to the apparatus by a conveyor 19 which moves the containers along the support into range of the arms of a rotating transfer device 20. This transfer device positively places the containers one after another in the pockets of the valve. Suitable guides 21, 21 are provided for directing the containers. An arm of the rotating transfer device 22 reaches into a pocket while the valve is rotating and removes the container from the pocket

- and positively conveys the same along the guide rails 23, 23 in the vacuum chamber and into range of a feed dog 24 on the conveyor chain 25. This conveyor chain 25 may be of any desired construction and is intended to indicate diagrammatically a form of feeding mechanism for feeding the containers in succession through the vacuum chamber 4. The conveyor is located wholly within the vacuum chamber.
- 10 The casing is provided with an extension 26 at the opposite end thereof from the valve 17. This extension is formed with a chamber 27 which communicates with the vacuum chamber 4. The casing also has an extension 28 providing a chamber 29 which communicates with the gassing chamber 5. There is also a central extension 30 which separates the two chambers 27 and 29. Mounted on the extensions 26, 28 and 30 is a valve seat 31 having an opening 32 leading to the chamber 27 and an opening 33 leading to the chamber 29. The valve seat is curved about a center 34. A valve seat 35 is fixed to the valve seat 31 and is curved about the same center 34. The valve seats 31 and 35, together with the connecting parts at the top and bottom thereof constitute a valve housing. A valve 36 is mounted within the valve housing for contact with the valve seats, and this valve rotates about a center 34, and in the direction of the arrow on the drawing. The valve 36 is similar in construction to the valve shown in the Troyer patent, and further detail description thereof is not thought necessary. The valve is provided with a series of pockets 37. Mounted for rotation in the chamber 27 is a transfer device 38. This transfer device takes the containers from the conveyor 25 and places the containers one after another in the pockets of the valve 36. Mounted in the chamber 29 is a rotating transfer device 39 which engages the container in the pocket and positively moves the container out of the pocket and places the same in the gassing chamber so that the dog 40 carried by the conveyor chain 41 will engage the container and carry the same through the gassing chamber. This conveyor chain 41 is diagrammatically illustrated and is intended to represent a conveying mechanism of any desired character. It is located wholly within the gassing chamber.
- 50 Located in the chamber 9 is a rotating transfer device 42 which moves into contact with the container on the conveyor chain 41 and positively forces the same into a pocket of the valve 17. A rotary transfer device 43 moves into the pocket 55 and strips the container from the pocket, delivering the same to a feeding mechanism 44 which conveys the containers away from the apparatus to the closing machine.
- The closing machine is set close to the treating 60 apparatus. The containers are preferably of the type wherein the ends are secured to the container bodies by double seaming. The cover is placed on the container and lightly clinched thereto before it passes into the apparatus. This 65 does not prevent the drawing of the vacuum on the container in the vacuum chamber and the relieving of the vacuum with an inert gas as the container passes through the gassing chamber. A pipe 45 is connected to the vacuum chamber 4 and any suitable vacuum creating means is connected to this pipe and operates to maintain the chamber 4 under continuous vacuum. A pipe 46 is connected to the chamber 5, and this pipe is adapted to be in turn connected to a suitable 70 means for supplying inert gas, such as carbon

dioxide gas to the chamber. The chamber is kept under a continuous supply of the carbon dioxide gas.

The chamber 7 is sealed by means of a door 47 which is hinged at 48. This enables ready access to the chamber 7 in case of a jam in the transfer of the containers from the valve to the conveying mechanism in the vacuum chamber. The chamber 27 is likewise provided with a hinged door 49 which seals an opening through which access 10 may be readily had to this chamber in case of a jam in the transfer of the containers from the conveying means 25 to the valve 36. There is a similar door 50 for the chamber 29 and a door 51 for the chamber 9.

In the operation of the device, the containers are fed in succession into the valve 17, and are transferred from the pockets of the valve to the conveying mechanism in the vacuum chamber 4. There are suitable guides 52, 52 for directing the containers through this vacuum chamber. The containers are taken one at a time from the conveyor and placed in a pocket of the continuously rotating valve 36, and this pocket transfers a container into range of the stripping device 39 which positively removes the container from the pocket and places the same on the conveyor in the gassing chamber. There are guide rails 53, 53 for directing the containers through the gassing chamber. When the pocket is in communication with the gassing chamber it will be filled with an inert gas, and the inert gas will be given up to the vacuum chamber 4 when brought into communication therewith. In this way, the containers are transferred from the vacuum chamber by a single valve to the gassing chamber with the feeding of a small amount of inert gas back into the vacuum chamber. This delivery of a small amount of inert gas into the vacuum chamber does not reduce to any great extent the vacuum, and to whatever extent it does reduce it, it is not diluted with air containing oxygen. In other words, the container after it is vacuumized is gassed under conditions of transfer from one chamber to the other, which avoids any admission of air to the container.

In the apparatus as described, there are substantially eight containers at a time within range of the vacuum pull for drawing air therefrom, and each container travels the full length of the 50 vacuum chamber so that it is subjected to a vacuum pull while it is traveling through the spacing of eight containers. If the machine is operating at the rate of forty containers per minute, then each container would be under vacuum 55 treatment for approximately twelve seconds. The same is true during the gassing of the containers.

It is understood that changes in the details of construction and the arrangement of the parts 60 may be made without departing from the spirit of the invention as set forth in the appended claims.

Having thus described the invention, what I claim as new and desire to secure by Letters 65 Patent, is—

1. An apparatus for vacuumizing and gassing containers comprising a casing, means extending longitudinally of the casing and dividing the same into two independent chambers, means 70 whereby one of said chambers may be placed under vacuum, means whereby the other chamber may be charged with an inert gas, said casing having a valve housing at one end thereof provided with a curved valve seat formed with open- 75

ings leading to the respective chambers, a single valve cooperating with said valve seat, said valve having a series of independent pockets for conveying containers to and from the respective openings, said casing at the other end thereof being provided with a valve housing having a curved valve seat with openings leading to the respective chambers, a single valve cooperating with said last-named valve seat and having a series of independent pockets for receiving and transferring the containers from one chamber to the other, means for conveying the containers in succession through the vacuum chamber, means for conveying the containers in succession through the gassing chamber, means associated with the valve at the receiving end of the vacuum chamber for transferring cans from the pockets thereof to the conveying means in the vacuum chamber, and means associated with said valve for removing containers from the conveying means in the gassing chamber and for placing the same in the pockets of said valve.

2. An apparatus for vacuumizing and gassing containers comprising a casing, means extending longitudinally of the casing and dividing the same into two independent chambers, means whereby one of said chambers may be placed under vacuum, means whereby the other chamber may be charged with an inert gas, said casing having a valve housing at one end thereof provided with a curved valve seat formed with open-

ings leading to the respective chambers, a single valve cooperating with said valve seat, said valve having a series of independent pockets for conveying containers to and from the respective openings, said casing at the other end thereof being provided with a valve housing having a curved valve seat with openings leading to the respective chambers, a single valve cooperating with said last-named valve seat and having a series of independent pockets for receiving and transferring the containers from one chamber to the other, means for conveying the containers in succession through the vacuum chamber, means for conveying the containers in succession through the gassing chamber, means associated with the valve at the receiving end of the vacuum chamber for transferring cans from the pockets thereof to the conveying means in the vacuum chamber, means associated with said valve for removing containers from the conveying means in the gassing chamber and for placing the same in the pockets of said valve, means associated with the valve at the discharge end of said vacuum chamber for removing containers from the conveying means in the vacuum chamber and transferring the same to the pockets in said valve, and means associated with said last-named valve for transferring cans from the pockets therein to the conveying means in the gassing chamber.
